UNITED STATES PATENT OFFICE

JOHN A. PHELAN, OF LANCASTER, PENNSYLVANIA, ASSIGNOR TO ARMSTRONG CORK COMPANY, OF LANCASTER, PENNSYLVANIA, A CORPORATION OF PENNSYLVANIA

MANUFACTURE OF INLAID LINOLEUM

Application filed June 9, 1930. Serial No. 459,869.

This invention relates to the manufacture of inlaid linoleum and provides a method of manufacture which is particularly suitable for use in connection with machines of the well-known rotary type. The invention will be herein described particularly with reference to its use in connection with a rotary machine, although in certain of its aspects it has numerous other applications.

10 The rotary machine consists essentially of a large drum about which travels the backing material impregnated with a mix coat of linoleum material. Webs of linoleum mix are formed by calenders above the level of 15 the drum and these webs are fed to die rolls which cut the linoleum into pattern elements and scrap. Strippers actuated by pin rolls within the die rolls eject the scrap material and lay the pattern elements on the backing.

20 There is a die roll for each color in the pattern and the usual practice is to employ two, three or four such rolls, so as to cover the entire surface of the backing with pattern elements.

25 Machines of this type are very expensive and require a relatively large crew for operation. It is, therefore, extremely important that shut downs and idle time be avoided. Unfortunately the machine is of such character that only a relatively limited variety of 30 patterns can be obtained. A further limitation on the character of the product is imposed by reason of the fact that the "grain" of the several webs of linoleum mix all runs longitudinally of the goods. In tile patterns 35 wherein the several blocks are grained to simulate marble the grain of each block is longitudinally of the goods and this is recognized as inferior in appearance to patterns where-

40 in some of the blocks have their grain running crosswise. It has been proposed, but so far as I am aware, it has never been the commercial practice to form the strippers of the die rolls in such fashion that some of them 45 are rotated through an angle so as to turn the died out pattern elements before laying them on the backing. This idea is not applicable to the rotary machines in commercial use because of space limitations and, therefore, the 50 commercial practice in the manufacture of

linoleum where the grain in different pattern elements runs in different directions has been to resort to the old practice of hand laying. The hand laying process is slow and expensive.

55

I provide for cutting a web of linoleum mix, laying cut out pieces on a backing and picking off the desired pieces and relaying them on the backing in a different orientation. If desired, several webs of linoleum mix may be employed and a pattern formed by operating the rotary machine in the usual fashion. However, the pattern will be modified by picking off certain of the elements which have been laid on the backing and re-laying them by hand so as to change their orientation. For certain types of patterns it may be desirable to cut a single web into pieces and lay these pieces on the backing, certain of them being picked off and relaid by hand. Highly desirable effects may thus be obtained and it is possible to use mixes which are ordinarily not considered feasible with a rotary machine. It has been stated above that in ordinary rotary machine patterns the grain always runs longitudinally of the goods. It has, therefore, been the practice to avoid bold marbles or variations in the marble or other textures imparted by the calenders so as to minimize this defect. By the 70 present process boldly textured marbles or other patterns may be employed and in fact their use is desirable in obtaining striking and ornamental effects.

75

Where a single web of linoleum mix is employed, there is no scrap loss, the entire web being cut into pieces and laid on the backing. This represents a marked saving over ordinary practice.

85

In practice, the pattern elements at the 90 sides of the material are made wider than is required in the finished material so as to leave an excess for trimming. This side border is necessary for various reasons. During the calendering operation wherein the pattern 95 elements are consolidated with one another and with the backing there is a tendency for the blanket of the calender to round off the edges of the material. There is also some stretching of the material and provision must 100

be made for trimming the goods to exact width. Obviously if it is desired to pick off some of the pattern elements along the sides of the material and relay them in a different orientation, the extra width normally provided on the outside pattern elements cannot be given. I, therefore, depart from the customary practice and make at least some of the pattern elements at the side, of the substantially desired final dimensions. I prefer to do this only with those pattern elements which are to be relaid by hand and extend the other pattern elements onto the waste portion of the goods. By this practice the sidewise extending pieces serve as an index of the pieces to be picked off and relaid. This is particularly desirable in goods made from a single web of linoleum mix. A great advantage of my method is that it can be carried out at relatively high speed but where the material is moving at such speed difficulty is sometimes encountered by the workmen in locating the particular pieces which are to be picked off. The indexing of the margin is very helpful in this regard.

In ordinary practice the pattern elements are laid firmly on the backing so as to adhere relatively strongly thereto. According to my method I prefer that the pieces be laid with relatively light pressure so that they may be readily picked off. It will be understood that the mix coat which is applied to the backing is relatively tacky and the uncured pattern elements will adhere thereto sufficiently to insure their staying in place until the calender is reached.

In the accompanying drawings illustrating a present preferred embodiment of the invention

Figure 1 is a diagrammatic view illustrating a rotary machine suitable for the practice of my invention.

Figure 2 is a view of a piece of linoleum made from a single web showing the material as it issues from the rotary machine and successive steps in the picking off and relaying of certain of the pattern elements; and

Figure 3 is a similar view showing a three color pattern.

The machine shown in Figure 1 comprises a drum 2 having die rolls 3 associated therewith. A web 4 of backing material is supplied to the machine and travels around the drum 2 so as to receive pattern elements which are laid on by the die rolls 3. A calender 5 is provided for each die roll 3 and the web W of linoleum mix supplied from the calender is carried by belt 6 to the die roll 3. The web travels between the die roll and a platen roll 7 and knives on the surface of the die roll cut the web into pieces. If a single web of linoleum mix is employed all of the web will be deposited on the backing 4. If in accordance with the usual practice two or more colors are employed the scrap from each

web will be ejected by strippers which are actuated by pin roll 8 inside the die roll. The scrap is received in trough 9 and carried away. Pin rolls 10 inside the die rolls 3 actuate strippers to lay on the backing those pieces of the linoleum mix which it is desired to use in the finished product. 70

The backing with the pattern elements thereon travels over an inspection table 11 to a roll calender 12 where the pattern elements are consolidated with the backing and one another. The pattern elements which it is desired to pick off and relay are lifted off the backing as the material passes over the inspection table 11 by workmen standing on each side of the table. 75

Figure 2 shows a conventional tile pattern made up of square blocks of a marbled mix. In the upper portion of the view the material is shown as it issues from the rotary machine. It presents the appearance of a continuous web of marbled material with no breaks therein except for the lines of severance between pieces, which lines are indicated at 14. The backing 4 is shown in the right hand side of the view and the marginal portion 15 of the linoleum, which margin must be trimmed off, is also illustrated. It will be noted that the row of blocks at the right hand side of the material is not uniform, alternate blocks being square and the blocks between them being rectangular and extending beyond the margins 16 of the square blocks. It is desired to turn alternate blocks in each row through an angle of 90° and relay them on the backing. By making the alternate blocks rectangular the workmen are provided with an index which shows them just which blocks are to be turned. 80

I have found in practice that it is desirable to use one or more workmen for each row of blocks or other pattern elements in a design. In Figure 2 I have shown a tile pattern. In this pattern half of the blocks must be picked off and relaid by hand. The number of workmen employed will depend on the speed at which the operation is performed. In Figure 2 I have indicated an operation on which two men are employed on each longitudinal row of blocks. A man standing at the station A will pick off, turn and relay every fourth block in the outermost row. Each block which has been turned by this workman is indicated by an a. A workman standing at B will pick up and relay the square blocks intermediate the blocks a. These blocks are indicated at b. Workmen at stations C and D correspondingly relay the blocks in the second course from the right of the view and workmen at stations E and F, G and H, J and K correspondingly turn the blocks in the 3rd, 4th and 5th courses. The bottom portion of Figure 2 shows the material after the blocks have been turned and the material is ready for calendering. 85 90 95 100 105 110 115 120 125 130 135 140

Figure 3 shows a multi-colored pattern employing several webs of linoleum mix. In the upper portion of the view the material is shown as it issues from the machine and at the bottom portion it is shown after the desired blocks have been reoriented.

I have illustrated and described a present preferred embodiment of the invention and have shown two patterns in illustration thereof. It may be understood, however, that this is by way of example only and that the invention may be otherwise embodied or practiced within the scope of the following claims.

15 I claim:

1. In the method of making inlaid linoleum, the steps consisting in forming a patterned web of linoleum mix, cutting the same into pieces, laying such pieces on a backing, picking off desired pieces, and relaying them on the backing in a different orientation.

2. In the method of making inlaid linoleum, the steps consisting in forming a patterned web of linoleum mix, cutting the same into pieces, laying such pieces on a backing, picking off desired pieces, and relaying them on the backing in a different orientation while leaving other pieces undisturbed.

3. In the method of making inlaid linoleum, the steps consisting in forming a patterned web of linoleum mix, automatically cutting the same into pieces, laying such pieces on a backing, manually picking off desired pieces and relaying them on the backing in a different orientation.

4. In the method of making inlaid linoleum, the steps consisting in forming a patterned web of linoleum mix, cutting the same into pieces, laying such pieces on a backing, picking off desired pieces, and relaying them on the backing in a different orientation, the pieces which are picked off lying at different intervals along the goods.

5. In the method of making inlaid linoleum, the steps consisting in forming a patterned web of linoleum mix, cutting the same into pieces, laying such pieces on a backing, picking off desired pieces, relaying them on the backing in a different orientation, and consolidating the pieces on the backing.

6. In the method of making inlaid linoleum in a rotary machine, effective for cutting a web of linoleum mix into pieces, laying such pieces on a backing, the steps consisting in supplying a patterned web of linoleum mix to the machine, picking off desired pieces laid on the backing by the machine and relaying them on the backing in a different orientation.

7. In the method of making inlaid linoleum, the steps consisting in forming a patterned web of linoleum mix, cutting the same into pieces and laying them on a backing, certain of such pieces being of such shape that they can be laid in different orientation

within the area defined by the adjacent pieces and other of said pieces being of another size or shape, picking off desired ones of the first mentioned pieces and utilizing the last mentioned pieces as an index of the pieces to be picked off and relaying such picked off pieces in a different orientation.

8. In the method of making inlaid linoleum, the steps consisting in forming a patterned web of linoleum mix, cutting the same into pieces and laying them on a backing, certain of such pieces laying along the edge of the goods, being of such shape that they may be laid in different orientation within the area defined by the adjacent pieces and other of said pieces along the edge projecting beyond the first mentioned pieces, picking off at least some of the first mentioned pieces and utilizing the last mentioned pieces as an index of the pieces to be picked off and relaying such picked off pieces on the backing in a different orientation.

9. In the method of making inlaid linoleum, the steps consisting in forming a patterned web of linoleum mix, cutting the same into pieces, laying such pieces lightly on a backing so that they may be readily picked off, picking off desired pieces and relaying them on the backing in a different orientation.

10. In the method of making inlaid linoleum in a rotary machine, having a die roll effective for cutting a web of linoleum mix into pieces and having strippers effective for laying such pieces on a backing, the steps consisting in feeding a patterned web of linoleum mix to the die roll, actuating the strippers in such fashion as to lay cut out pieces lightly on the backing material, picking off desired pieces and relaying them on the backing in a different orientation.

11. In the method of making inlaid linoleum in a rotary machine, effective for cutting a web of linoleum mix into pieces and laying such pieces on a backing, the steps consisting in supplying a web of linoleum mix to the machine, cutting the same in the machine, laying the entire web on the backing and picking off the desired pieces and relaying them on the backing in a different orientation.

12. In the method of making inlaid linoleum, the steps consisting in forming a patterned web of linoleum mix, the web being of an area equal to the desired area of the finished goods with an excess at the sides for trimming, cutting the same into pieces, laying such pieces together with the excess material at the sides of the web on a backing, the several pieces occupying the same relative position on the backing as they occupied in the uncut web, picking off desired pieces and relaying them in a different orientation.

13. In the method of making inlaid linoleum in a rotary machine effective for cut-

ting a web of linoleum mix into pieces and laying such pieces on a backing, the steps consisting in supplying a patterned web of linoleum mix to the machine, cutting the same into pieces thereby and laying them on the backing with the lines of the pattern running longitudinally of the backing, picking off desired pieces laid on the backing by the machine and relaying them on the backing in a different orientation so that the pattern lines of such pieces extend at an angle to the longitudinal dimension of the backing.

In testimony whereof I have hereunto set my hand.
